CLAIM

The ornamental design for a dust collector enclosure for saw, as shown and described.

DESCRIPTION

FIG. 1 is a left front perspective of a dust collector enclosure for saw, showing my new design;

FIG. 2 is an elevational view of the right side, thereof, the left side elevational view being a mirror image, thereof;

FIG. 3 is a front elevational view, thereof;

FIG. 4 is a top plan view, thereof;

FIG. 5 is an bottom plan view, thereof;

FIG. 6 is a rear elevational view, thereof; and,

FIG. 7 is a left front perspective view in environment, the broken-line representation of the vacuum and hose, the support table, and the electric saw with cord and socket, being included solely for illustrative purposes, forming no part of the claimed design.
